UNITED STATES PATENT OFFICE.

FRANK H. DOANE, OF SAN FRANCISCO, CALIFORNIA.

DESIGN FOR A SHOCK-ABSORBER.

45,800.

Specification for Design.

Patented May 19, 1914.

Application filed December 1, 1913. Serial No. 804,118. Term of patent 14 years.

To all whom it may concern:

Be it known that I, FRANK H. DOANE, a citizen of the United States, residing in the city and county of San Francisco and State of California, have invented a new, original, and ornamental Design for Shock-Absorbers, of which the following is a specification, reference being had to the accompanying drawing, forming part thereof.

The figure is a side elevation.

I claim:

The ornamental design for a shock absorber, as shown.

FRANK H. DOANE.

Witnesses:

H. T. FEYGE,

W. W. HEALEY.
